(57) **CLAIM**

The ornamental design for a shoe, as shown and described.

DESCRIPTION

FIG. 1 is a rear perspective view of a shoe showing my new design;
 FIG. 2 is a side view thereof;

FIG. 3 is a front perspective view thereof; and,

FIG. 4 is an enlarged view of the claim as shown in FIG. 2 with environment removed for clarity purposes.

The broken lines immediately adjacent to the photographic area define the bounds of the claimed design and form no part thereof. The broken lines depicting the remainder of the shoe form no part of the claimed design.
